(57) **CLAIM**

The ornamental design for an immuno-chromatography inspection machine, as shown and described.

DESCRIPTION

FIG. 1 is a top, front, right perspective view of an immuno-chromatography inspection machine, showing my new design in a first configuration with the shutter closed;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom, front, right perspective view of the shutter of FIG. 1, shown enlarged for clarity of disclosure;

FIG. 9 is a cross-sectional right elevation view of the immuno-chromatography inspection machine of FIG. 1, taken along the line of 9-9 of FIG. 6;

FIG. 10 is a cross-sectional right elevation view of the immuno-chromatography inspection machine of FIG. 1, shown in a second configuration with the shutter rotated open towards the rear;

FIG. 11 is a cross-sectional right elevation view of the immuno-chromatography inspection machine of FIG. 1, shown in a third configuration with the shutter rotated open towards the front;

FIG. 12 is a cross-sectional right elevation view of the immuno-chromatography inspection machine of FIG. 10, shown in a first condition of use;

FIG. 13 is a cross-sectional right elevation view of the immuno-chromatography inspection machine of FIG. 9, shown in a second condition of use; and,

(Continued)

FIG. 14 is a cross-sectional right elevation view of the immuno-chromatography inspection machine of FIG. 11, shown in a third condition of use.

In the drawings, the broken lines depict portions of the immuno-chromatography inspection machine that form no part of the claimed design. In FIGS. 12-14, the broken lines showing a cartridge depict environmental structure that forms no part of the claimed design. All broken lines form no part of the claim
